COMBINED NOSE GUARD AND SUN REFLECTOR
FOR TANNING THE FACE

Frances R. Ruskin, 32 E. 67th St., New York, N.Y.

Filed July 12, 1960, Ser. No. 61,311

Term of patent 14 years

(Cl. D83—1)

FIG. 1 is a perspective view of a combined nose guard and sun reflector for tanning the face embodying my new design;

FIG. 2 is a view in front elevation thereof; and FIG. 3 is a view in rear elevation, thereof.

I claim:

The ornamental design for a combined nose guard and sun reflector for tanning the face as shown.
